CLAIM

The ornamental design for a travel safety razor, as shown and described.

DESCRIPTION

FIG. 1 is an upper right side perspective view of a travel safety razor showing my new design;
FIG. 2 is a front end elevational view of the razor shown in FIG. 1;
FIG. 3 is a right side elevational view thereof, the left side being identical thereto;
FIG. 4 is a top plan view thereof;
FIG. 5 is a bottom plan view thereof; and,
FIG. 6 is a rear end elevational view thereof.
